SYLVESTER L. JOINER, OF SWEETWATER, TEXAS, ASSIGNOR OF ONE-THIRD TO ALEXANDER S. KENDRICK AND ONE-THIRD TO WALTER W. DAVIS, OF SWEETWATER, TEXAS.

ATTACHMENT TO AIR BRAKE PRESSURE RETAINING VALVES

Application filed September 28, 1931. Serial No. 565,650.

This invention relates to an attachment to air brake pressure retaining valves. It is an attachment adaptable for connection with the exhaust port of a standard air pressure brake retaining valve which will effectively prevent the depositing of solid matter in the port by insects and the like.

One object of the invention is to provide an attachment adaptable for connection with the exhaust port of a standard air pressure brake retaining valve which will effectively prevent the depositing of solid matter in the port by insects and the like. Another object of the invention is to provide a simple inexpensive attachment which will allow the air to exhaust from the exhaust port of an air brake pressure retaining valve and also prevent the clogging up or stopping up of the exhaust port by insects and the like, depositing foreign matter therein.

With these and other objects in view the invention will be more clearly understood by referring to the enclosed drawings, where in, Figure 1 is a side elevation of a standard air brake pressure retaining valve with my invention shown attached to the exhaust port; Fig. 2 is an enlarged vertical sectional view broken away to show the closure; Fig. 3 is a transverse sectional view taken on the lines 3—3 of Fig. 2 looking in the direction of the arrows; Fig. 4 is a transverse sectional view showing a modification of a closure; Fig. 5 is a transverse sectional view taken on the lines 5—5 of Fig. 4; Fig. 6 is a vertical section of a further modification of my invention; Fig. 7 is a transverse view taken on the lines 7—7 of Fig. 6 looking in the direction of the arrows; and Fig. 8 is a transverse sectional view taken on the lines 8—8 of Fig. 6 looking in the direction of the arrows.

Referring more particularly to the drawings, *a* denotes a standard air brake pressure retaining valve having an inlet *b* for exhaust air from the triple valve at the braking system of railroad cars and an exhaust port or opening *c*.

My invention generally indicated at 1, is shown attached to the exhaust port *c* of the air brake pressure retaining valve. The attachment 1 consists of the hollow open ended

nipple having an angular portion 2, and a substantially vertical portion 3. At the outer end of the angular portion there are provided screw threads 4 for attachment with the exhaust port *c*. Adjacent the outer end there is provided a wrench receiving portion 5 forming a shoulder 6. The other end of the nipple 1 has attached thereto, in any suitable manner, a pocket 7. Pivoted attached, as at 8, to the pocket 7 there is shown a closure 9. The closure being pivoted on a pintle 10 which extends through the sides 11 of the pocket and also through ears 12 of the closure. The closure consists of a substantially round portion 13 and an extension 14. The ears 12 are preferably integral with the extension of the closure, as shown at 15. Arranged in the pocket adjacent its outer end there is provided a compression spring 16 which normally maintains the closure 9 in engagement with the end 17 of the hollow nipple.

In the modification of my invention shown in Figs. 4 and 5, there is provided the nipple 1, consisting of the angular portion 2 and the substantially vertical portion 3. Adjacent the outer open end of the hollow nipple 17 there is provided a lug 18 which extends laterally from the side of the vertical portion of the nipple 3. This lateral extension is provided with an opening 19. Pivotedly mounted by means of the pintle 20 there is shown a closure 21. This closure consists of a substantially round portion 22 for covering the open end 17 of the nipple and has integral therewith an extension 23. This extension preferably has integral therewith suitable ears 24. These ears are provided with openings 25 to receive the pintle 20 which extends through the ears and through the opening 19 in the lug 18, thereby forming a pivotal mounting for the closure 21. At the outer end of the extension 23 there is shown a weight 26. This weight normally tends to maintain the closure 22 in engagement with the open end 17 of the hollow nipple. While the weight 26 has been shown attached to the extension 23 in any suitable manner, as at 27, it is to be understood that the extension itself might be increased in

size to serve the purpose. The weight 26 is shown attached to the extension 23 in any suitable manner, as at 27, it is to be understood that the extension itself might be increased in size to serve the purpose.

width and serve the same purpose of the weight, that is, to normally maintain the closure 22 in engagement with the open end 17 of the nipple.

- 5 In a modification of the invention shown in Figs. 6, 7 and 8 there is provided a nipple 1 with the angular portion 2 and the substantially vertical portion 3 having the screw threads 4 at the upper end of the angular portion 10 for engagement with the exhaust port *c*. The angular portion 1 of the modification shown in Fig. 6 is of substantially less diameter than the vertical portion 3. This angular portion provides a restricted 15 passageway for the exhaust air from the air brake pressure retaining valve. The vertical portion of the nipple is substantially twice the diameter of the angular portion 1 and is preferably of circular formation. In the 20 vertical portion of the nipple there is shown a flap valve 28 which is pivotally mounted on the pintle 29, the pintle 29 being secured in the vertical portion at opposite sides, as at 30. It will be seen that the portion of the 25 flap valve 31 extends over the passageway 32 formed by the angular portion of the nipple and normally closes this passageway. The opposite side of the flap valve 32 extends into a pocket 33 formed in the vertical 30 portion of the nipple and is provided preferably on its bottom side with a weight 34. The side wall of the vertical portion of the nipple is provided with a lug 35 forming a stop for the downward movement of the portion 32 of the flap valve. At the outer end 36 of the vertical portion of the nipple there may be provided a reticulated screen closure 37 secured to the nipple in any suitable manner, as at 38.
- 40 In the invention as disclosed in Figs. 1 to 5, it will be seen that I have provided a pivoted closure which is normally maintained in engagement with the open end of the nipple, thereby closing the same. I have shown a 45 spring and weight which normally maintains this closure in its closed position. When the air exhausts from the exhaust port *c* into the nipple it will be sufficient to open the closure to allow the air to exhaust from the 50 nipple and after the air has exhausted from the nipple the spring and weight will serve to automatically close the open end of the nipple.

In the modification shown in Fig. 6 it will 55 be seen that the incoming exhaust air from the port *c* to the passageway 32 engages only one portion of the flap valve and is sufficient to rock the flap valve from the full line position shown in Fig. 6 to the dotted line position shown therein, which enables the air to exhaust through the screen closure at the lower portion of the nipple. The weight on the flap valve serves to normally close the 60 passageway 32 and the pocket above the 65 weighted portion of the valve is adapted to

receive this portion of the valve when the exhaust air contacts with the other side of the flap valve.

The primary purpose of my invention has been to provide a simple and inexpensive attachment to the exhaust port of a standard air pressure retaining valve which will absolutely prevent insects from depositing solid matter, or other foreign matter in the exhaust opening of the valve but which will allow of the exhaust air to be exhausted through the nipple to the atmosphere and after such air has been exhausted the open end of the nipple will be automatically closed.

There has been considerable difficulty encountered in that, the exhaust ports of standard air brake pressure retaining valves are usually left open and when the cars remain on a siding for any length of time insects, such as sand daubers, deposit dirt and other foreign matter in the exhaust port thereby preventing proper exhaustion of the air therefrom, and in some instances causing serious accidents and a detrimental effects to the braking equipment of railway cars.

From the foregoing it will be seen that I have overcome this serious disadvantage and have provided an attachment which will prevent the clogging up of the exhaust port of the standard air brake pressure retaining valve.

It will be understood that various changes in the form, proportion, and minor details of construction, within the scope of the claims, may be resorted to without departing from the spirit of the invention or sacrificing any of the advantages thereof.

What is claimed is:

1. An attachment for air brake pressure retaining valves comprising a hollow nipple having an angular and vertical portion, said angular portion being adapted to be attached to the exhaust port of said valve, the said vertical portion being provided at its extreme open end with a pivoted spring pressed closure normally closed to prevent insects and the like from depositing solid matter in said exhaust port, but adapted to be opened by the exhaust of air and other foreign matter from said port.

2. An attachment for air brake pressure retaining valves comprising a hollow nipple one end of which is adapted to be attached to the exhaust port of said valve, a pivoted closure for the other end of the nipple, and means for maintaining said pivoted closure in its normal closed position to prevent insects and the like from depositing solid matter in said exhaust port, but allowing opening of said closure by the exhaust of air and other foreign matter from said port.

3. An attachment for air brake pressure retaining valves comprising a hollow nipple having an angular and vertical portion, said angular portion being adapted to be attached

to the exhaust port of said valve, a pivoted closure attached to the outer end of the vertical portion, and a weight attached to said closure to normally maintain the same in closed position to prevent foreign matter from being deposited in said port but allowing opening of said closure by the exhaust of air and other foreign matter from said port.

4. An attachment for air brake pressure retaining valves comprising a hollow nipple one end of which is adapted to be attached to the exhaust port of said valve, a pivoted closure attached to and having an extension projecting beyond the periphery of the other end of said nipple, and a spring acting on said extension to normally maintain the closure in closed position to prevent foreign matter from being deposited in said port but allowing opening of said closure by the exhaust of air and other foreign matter from said port.

5. An attachment for air brake pressure retaining valves comprising a hollow nipple provided with an enlarged valve chamber and an air exhaust passage of less diameter than said chamber adapted for attachment with the exhaust opening of said valve, a valve mounted in said chamber, means for normally maintaining said valve in closed position to prevent insects and the like from depositing foreign matter in said port, but allowing opening of said valve by the exhaust of air and other foreign matter from said port.

6. An attachment for air brake pressure retaining valves comprising a hollow nipple provided with a valve chamber and an air exhaust passage adapted for attachment with the exhaust opening of said valve, said valve chamber being of a larger diameter than said exhaust passage, a valve pivotally mounted in said valve chamber and having a portion extending over said exhaust passage forming a closure, the other portion of the valve being weighted, and means in said valve chamber to limit the downward movement of the weighted portion of the valve, whereby one portion of the pivoted valve normally closes said exhaust passage to prevent insects and the like from depositing solid matter in said port but allowing said valve to be opened by the exhaust air from said port through said passage.

7. The combination with an air brake retaining valve having an exhaust port, of a hollow nipple one end of which is adapted to be attached to said port, and having adjacent its other end a lug extending laterally therefrom, a closure pivoted to said lug, a weight on said closure to maintain the same in engagement with the said other end of the nipple to prevent insects and the like from depositing solid matter in said exhaust port but allowing said closure to be opened by the exhaust air from said port.

8. In combination with an exhaust port of an air brake retaining valve, of a hollow nipple having an angular and vertical portion, said angular portion being adapted to be attached to the exhaust port of said valve, said vertical portion being provided adjacent its open end with an integral, laterally extending lug, a closure for the open end of the nipple, said closure being pivoted to the said lug and having a weighted extension which normally maintains the closure in engagement with the outer end of the nipple to prevent insects and the like from depositing solid matter in said exhaust port, but allowing opening of said closure by the exhaust air and other foreign matter from said port.

In testimony whereof, I affix my signature this 26th day of September, 1931.

SYLVESTER L. JOINER.
